CLAIM

The ornamental design for a fixing bracket for display panel as shown and described.

DESCRIPTION

1. Fixing bracket for display panel

1.1 : Perspective

1.2 : Bottom perspective view

1.3 : Front

1.4 : Left

1.5 : Top

1.6 : Bottom

The rear view is omitted because it is a mirror image of the front view; the right side view is omitted because it is a mirror image of the left side view.

1 Claim, 6 Drawing Sheets
